ELECTROMAGNETIC SWITCH

Raymond H. Sullivan, Rochester, N. Y., assignor
to North East Appliance Corporation, Rochester, N. Y., a corporation of New York

Original application May 29, 1930, Serial No.
457,112. Divided and this application August
13, 1931, Serial No. 556,831

3 Claims. (Cl. 200—87)

This invention relates to apparatus for controlling an electrical system, and more particularly to an electromagnetically controlled switching or relay device.

5 One of the objects of the invention is to provide a switch for purposes such as automatically controlling a circuit including a battery and a generator for charging the battery, which switch operates at a substantially predetermined voltage regardless of temperature change.

A further object of this invention is to provide a switch or relay device in which there is less tendency for the contacts to stick together.

This application is a division of application Serial No. 457,112, filed May 29, 1930 which has been issued as Patent No. 1,968,971.

Further objects and advantages of the present invention will be apparent from the following description, reference being had to the accompanying drawings wherein a preferred embodiment of the present invention is clearly shown.

In the drawings:

Fig. 1 is a sectional view taken substantially on the line 1—1 of Fig. 2, and looking in the direction of the arrows.

Fig. 2 is a fragmentary top view of the switch or relay device shown in Fig. 1.

Fig. 3 is an exploded view of the switch or relay device shown in Figs. 1 and 2.

30 The switch or relay device comprises chiefly three subassemblies,—a base subassembly, a magnet subassembly and an armature subassembly. The magnet subassembly comprises an assembly of electromagnets of the switch, this subassembly

35 being attached to the base subassembly by riveting thereto the central cores of the electromagnets. The armature subassembly is then attached to the magnet subassembly. The base

40 subassembly comprises a base frame 20 having legs 21 by which the base may be attached to a support, such as the cylindrical frame of the dynamo-electric machine. An insulating plate 23 is secured to the upper side of the base frame 20 by rivets such as 22, or other suitable fastening

45 means. Plate 23 has holes 26 in alignment with the larger holes 27 in the base 20. These holes receive magnet cores, to be described later. On the underside of the base 20, are located two nonconducting plates 28 having holes 29 in alignment with the holes 26 through the plate 23, and substantially the same size as the latter holes.

50 The plates 28, together with metallic terminal plates 31 and 32, are attached to the base plate by rivets such as 35, or other suitable fastening means, fastened through aligned holes in the

terminal plates 31 and 32, insulating plates 28, base 20 and insulating plate 23. The holes in the base 20 through which the rivets 35 pass are larger in diameter than the rivets, so that the base 20 is not electrically connected to the terminal plates. 5

The magnet subassembly comprises an assembly of two magnet cores and an armature hinge plate subassembly, magnet windings and insulating plates placed upon the cores adjacent the ends of the windings. This subassembly comprises cores 40 and 41, the upper ends of which are attached to a subassembly including an armature hinge and stop plate 42 having ears 43 provided with holes 44 that are preferably threaded, and having a stop lug 45 that is preferably substantially T-shaped. The hinge plate 42 is preferably secured to a magnetic shunt plate 47, the magnetic permeability of which varies with temperature. The plate 47 is provided with two large holes 48 which receive magnetizable washers 49, which washers are preferably secured in their respective holes by staking, or by other suitable means. Upper reduced end portions 51 of the magnet cores 40 and 41 pass through aligned holes in the hinge plate 42 and washers 49, and are riveted over against the washers. 10 15 20 25

An insulating plate 72 is provided for assembling the switch with an adjacent unit, not shown, and this plate has holes 70 for receiving the cores 40 and 41. The plate also preferably has notches such as 73 and an oblong hole 74 therein. Following the assembling together of the armature hinge plate and the core subassembly, the magnet coils 80 and 81, previously wound upon forms, are placed around the cores 40 and 41 respectively. In the particular form shown, before assembling the coil 80 upon the core 40, the form wound coil 82 is assembled upon the coil 80. Following this, an insulating plate 83 is placed upon the cores 40 and 41 to insulate the ends of the coils 80 and 81, and to tie the lower end of the cores 40 and 41 together in proper spaced relation. Then a spring hooked plate 84 is assembled upon the projecting ends of the cores 40 and 41. This assembly of magnet cores, magnet coils, armature hinge plate, magnetic shunt and spring hooked plate is attached to the base subassembly by passing the shanks at the lower ends of the cores through the holes 26, 27 and 29 of the parts of the base subassembly; these shanks being then riveted over against washers 95. The magnet coils are preferably encased in a wrapping of insulating material, as indicated at 96 in Fig. 3. 30 35 40 45 50 55

The relay armature subassembly comprises a rigid armature plate 100 attached by rivets 101, or other suitable fastening means, to an insulating plate 102, which plate is attached by rivets 103, or other suitable fastening means, to a flexible spring conductor 104. The flexible spring conductor 104 has a wire receiving hook 105 at one end, and carries at the other end a contact 106, which contact cooperates with a contact 107 that is carried by the armature plate 100. The contact which is positive is preferably silver, and the contact which is negative is preferably tungsten. The spring conductor 104 carries a fiber bumper block 110 having a shank 111 passing through a hole in the spring 104, and having a groove 112 which receives a spring clip 113 which detachably secures the bumper block 110 to the spring 104. The contact 106 is welded to the plate 108 having a shank 109 which passes through the spring 104 and is riveted over against a washer 109a located upon the upper side of the spring 104. The armature 100 carries a non-magnetizable rivet 115 which prevents actual contact between the armature 100 and the pole pieces of the magnet that are provided by the upper ends of the cores 40 and 41. Some of the rivets 101 secure to the armature 100 a leaf spring hinge plate 116 having apertured ears 117 through which screws 118 pass. The screws 118 are threaded into the holes 44 in the ears 43 of the hinge bracket 42. When the armature subassembly is attached to the magnet subassembly in this manner, a spring 119 is attached to the hook plate 42 and to a notched end 120 of the armature 100. This spring urges the armature 100 in a counter-clockwise direction as viewed in Fig. 1. Before attaching the armature 100 to the hinge plate 42, the T-shaped lug 45 is passed through an opening 121 in the armature 100, and then the armature 100 is moved edgewise to locate the holes for the screws 118 and to align those holes with the holes 44 and the bracket 42. When so moving the armature, the shank of the T-shaped lug 45 is located into an opening 122 that is smaller in width than the head of the lug 45. Therefore, the head of the lug 45 operates to provide a stop that engages the upper surface of the armature 100 to limit movement of the armature away from the magnet, as effected by the spring 119. When the armature is attached to the hinge plate, the bumper block 110 is located above the lug 45, and is normally spaced therefrom.

The magnetic shunt 47 preferably has a negative temperature coefficient of magnetic permeability, and is preferably made of a special alloy of nickel and steel, so constituted that it will cause the relay to operate similarly, at substantially a predetermined voltage, regardless of temperature. That is, the magnetic shunt is preferably so constituted that as the temperature increases, the permeability of the shunt 47 becomes lowered to tend to cause more flux to link the armature and vice versa. This magnetic shunt 47 also preferably compensates for the increase of resistance in the windings of the electromagnets that is effected by an increase in temperature. When the voltage impressed upon the electromagnet coils 80 and 81 is in excess of a certain value, the armature 100 is attracted toward the cores 40 and 41 against the action of the spring 119 which normally holds the armature against the stop 45. As the armature 100 moves toward the cores 40 and 41, the leaf spring conductor 104 tends to follow the

armature until movement of that conductor is arrested by the bumper block 110 striking the stop 45. Further movement of the armature 100 toward the cores 40 and 41 effects the separation of the contacts 106 and 107. When the voltage decreases or is below a certain value, the armature and leaf spring conductor return to their normal positions.

As previously mentioned, in the particular switch shown, a winding 82 is provided which surrounds a portion of the outside of one of the electromagnets. In this particular switch, this winding 82 is preferably of relatively few turns of relatively coarse wire, and is connected in series with the contacts 106 and 107. The winding 82 assists the windings 80 and 81 to separate the switch contacts. However, when the contacts are separated, the magnetic effect of the winding 82 is altered thereby. It is understood, however, that in many instances this additional winding 82 is not necessary to the operation of switch, and may be eliminated. One of the advantages of utilizing the coil such as 82 is that in case the contacts tend to stick together, coil 82 materially assists in opening the contacts.

The temperature compensating magnetic shunt is particularly desirable when the switch is utilized for the control of apparatus such as an automobile generator, and where wide variations in temperature are encountered. That is, in the control of an automobile generator, there are not only the variations in temperature that occur in different weather, but also the temperature depending upon that of the automobile engine. In this particular application, it is very desirable to have the switch operate consistently in spite of the wide variations in temperature.

It has been found that a satisfactory alloy for making the magnetic shunts of the switch is one having the following analysis:

	Per cent
Carbon	Max. .10
Manganese	.050 - 1.00
Silicon	Max. .15
Phosphorus	Max. .030
Sulphur	Max. .045
Nickel	30, 25-30.75

The bumper block 110 cooperates with the stop 45 to cause the blade 104 to bend about stop 45 as a fulcrum as the armature 100 moves toward the regulator magnet to separate the contacts 106 and 107. Since the armature 100, carrying contact 107, bends about a fulcrum substantially removed from the fulcrum about which the blade 104, supporting contact 106, bends just before contact separation, contact 106 will teeter or rock upon the contact 107 before separation takes place. This rocking motion tends to allow the contacts to become separated easily, and minimizes sticking.

While the embodiment of the present invention as herein disclosed, constitutes a preferred form, it is to be understood that other forms might be adopted, all coming within the scope of the claims which follow.

What is claimed is as follows:

1. An electromagnetic switch comprising, in combination, a base; a pair of magnet cores insulatingly secured at one end to the base, and having windings thereon; an armature hinge bracket secured to the other ends of the cores; an armature carrying a contact and hingedly connected with the bracket; a cooperating contact insulatingly mounted to the base through a contact support; a spring bracket insulatingly se-

cured to the base intermediate the winding and base; and a spring connecting the spring bracket and armature.

2. An electromagnetic switch comprising, in combination, a base; a pair of magnet cores insulatingly secured at one end to the base, and having windings thereon, said cores being secured to the base by riveting the ends thereof; a spring bracket insulatingly secured to the base intermediate the winding and base; an armature hinge bracket and a temperature responsive magnetic shunt having corresponding apertures therethrough, through which the cores extend, said bracket and said shunt being secured to the cores by riveting the ends of the cores; an armature 10 hingedly connected with the bracket and carrying a contact; a cooperating contact; a spring connected to the spring bracket and armature to bias the armature away from the cores; said windings being connected electrically to effect 15 movement of said armature toward the cores against the biasing force of the spring, and said magnetic shunt effecting a change in the flux linking said armature as the temperature changes; and a stop integral with the hinge 20 bracket and extending through the armature to arrest motion of the contact in one direction.
3. An electromagnetic switch comprising, in combination, a base; a pair of magnet cores in-

sulatingly secured at one end to the base, and having windings thereon, said cores being secured to the base by riveting the ends thereof; a spring bracket insulatingly secured to the base intermediate the winding and base; an armature hinge bracket and a temperature responsive magnetic shunt having corresponding apertures therethrough, through which the cores extend, said bracket and said shunt being secured to the cores by riveting the ends of the cores; an armature 10 hingedly connected with the bracket and carrying a contact; a cooperating contact; a spring connected to the spring bracket and armature to bias the armature away from the cores; said windings being connected electrically to effect 15 movement of said armature toward the cores against the biasing force of the spring, and said magnetic shunt effecting a change in the flux linking said armature as the temperature changes; and a stop integral with the hinge 20 bracket and extending through the armature to arrest motion of the contact in one direction.
